SHEET INSERTING MECHANISM

Original Filed July 14, 1927 2 Sheets-Sheet 2

UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

SHEET-INSERTING MECHANISM

Application filed July 14, 1927, Serial No. 205,718. Renewed June 19, 1929.

This invention relates to newspaper printing presses in which one or more webs are fed into a folder at full speed with another sheet fed in, preferably between them, at half speed so as to vary the number of pages in successive papers. This is an improvement over my application for patent on a half speed sheet inserting mechanism Ser. No. 152,402, filed December 3, 1926.

10 The principal objects of this invention are to provide means whereby the rebound due to the snap of the paper when the connecting nibs between successive slits are torn apart will be avoided; to provide at a point in line 15 with the rear end of the sheet means which, at the moment of the severance of the sheet, will momentarily hold the leading end of the web and keep it from rebounding when the preceding sheet is being severed therefrom; 20 to provide for the registering of the half speed sheet by its rear edge instead of its front edge, as was done in the above mentioned application by severing the half speed sheets at two separate points instead of one; 25 to provide a more efficient means for registering the insert sheets in the form of a secondary cutting device arranged to penetrate at full speed the webs at such points, or nibs, as have been left un-cut by the primary cutting cylinders; and to provide means 30 for further maintaining register between the half and full speed sheets in the form of pins, preferably blunt, on the periphery of one of the full speed folding rollers to punch a 35 ragged hole in the three sheets which on account of the turning back of the torn edges forms a temporary slit or lock between them to prevent the center sheet from shifting and losing its register.

40 Other objects and advantages of the invention will appear hereinafter.

Reference is to be had to the accompanying drawings, in which

45 Fig. 1 is a side view of a diagrammatic nature of one form of the invention, showing the arrangement of the feeding and cutting members of the press and their relation to the drag roll and former;

50 Fig. 2 is a plan of a part of the same,

showing the relationship of the half speed web to one of the full speed webs;

Fig. 3 is an enlarged sectional view through the roller for holding the leading end of the web;

Fig. 4 is a view similar to Fig. 1 of a preferred construction in which a secondary cutting cylinder is substituted for the roller shown in Fig. 3 and

Fig. 5 is a plan of the same similar to Fig. 2.

In my above specified application two or more webs of paper *w* are fed into a folder 10 at full speed and an intermediate web *w'* is fed into the folder at half the speed of the other webs. This is done for the purpose of varying the number of pages in successive papers so that, for example, every other paper may have two extra pages taken from the web *w'*. The folder has a former as usual 10 and cutting and folding cylinder 9. The web *w'* is fed between a pair of half speed cutting cylinders 11 and 12. One of these cylinders is provided with a knife or blade 13 which extends along it and is provided with cutting edges at intervals so as to produce perforations 14 or slits leaving the web connected at spaces 15 between them. These slits of course extend transversely of the web. They are formed so that, when the sheet ahead is pulled, the web will be separated along the line of perforations. That sheet could pass along into the folder without interference from the web *w'* behind it, which is held back by the fact that the surface speed of the cylinders 11 and 12 is only half the speed of the other webs. This web *w'* passes in between the two webs *w* which are brought in over guide rollers 16 and conducted through a horizontal space from these 85 guide rollers to the drag roll 17. This directs them into the former of the folder 10. The drag roll runs at a surface speed equal to that of the webs *w*. Above the drag roll is provided a shaft 18 on which are mounted a series 90 of arms 19 each one having a stud 21 for a propeller roller 25. This roller has a portion of its circumference 26 reduced so that it does not come into contact with the lower roll 24 during a part of the rotation.

The half speed web is fed in between the full speed webs in the horizontal path described. When the larger part of the roll 25 is in contact with the lower roll 24, these webs are nipped between these rolls. The half speed length is located between the two full speed webs and it will have to move at the same speed as the two outer webs. The object of this is to tear the forward sheet from the web *w'* and forward this sheet at full speed.

While this effectively starts the half-speed sheets into the folder at full speed, it may permit the leading edge of the web to rebound due to the snap of the paper and thereby lose its register. In order to avoid this I have provided at a point in line with the rear end of the sheet, as shown in Fig. 1, a timed roller 20 which at the moment of severance of the sheet will momentarily hold the leading end of the web and keep it from rebounding when the sheet preceding it is severed therefrom. This is accomplished by a spring seated section 22 which is carried by the cylinder 20 co-acting with a roller 23 directly above it. Thus register is maintained at all ends, both in the severed sheet as well as in the incoming web.

Any tearing action by the roll 25 produces a rebound in the incoming web due to the natural elasticity of the paper, a quantity which may vary from time to time due to the likelihood of the paper varying in strength under varying weather conditions. 35 In order to check this rebound, which helps to disturb the register between the half and the full speed webs, I prefer to provide, as shown in Fig. 4, a pair of secondary cutting cylinders 30 which are equipped with a line 40 of knives 32 so arranged as to penetrate at full speed the three webs at such points 31 as have been left uncut by the primary cutting cylinder. Thus, the half-speed web is partially cut by the primary cutting cylinder 45 knife 13, fed into the bite of the two full speed webs; and when the front edge of the half speed web comes into the bite of the folding rollers the nibs 15 are cut apart by the knives 32 in the secondary cutting cylinder. The latter are narrow enough to leave 50 but short cuts in the full speed sheet as they penetrate to reach the half-speed sheet. By severing the half speed sheets at two separate points instead of one, they are registered at 55 their rear edges instead of at their front edges.

To further maintain register between the half and the full speed sheet I provide a number of pins 33, preferably of the blunt type, 60 on the periphery of one of the full speed forwarding rollers 34. These pins are made to register with the margins of the paper so that the perforations may not affect the printed page. A row of pins may be placed either 65 in the transverse margin across the sheet, or

the longitudinal margins, or in both the transverse and longitudinal margins. These pins punch a ragged hole 35 in the three sheets of paper, turning back the torn edges of the hole through the several sheets, thereby forming an effective seal or lock between them. This prevents the center sheet from shifting and losing its register with the outside sheet. In this invention, therefore, I have provided for a complete register at the front edge, between the several sheets, and have completely eliminated any tendency for variations in that register by rebound or other disturbances due to a tearing of the paper.

Although I have illustrated and described two forms of the invention, I am aware of the fact that other modifications can be made therein by any person skilled in the art without departing from the scope of the invention as expressed in the claims.

Therefore, I do not wish to be limited to the details of construction except as set forth in the claims, but what I do claim is:

1. In a web feeding device for a printing machine, the combination with means for feeding a pair of webs, of means for feeding a web between them at half speed, means for separating the half speed web into sheets and means for maintaining the half speed sheets in registration at their rear ends.

2. In a web feeding device for a printing press, the combination with means for forwarding a plurality of webs at different speeds, of a cutting couple arranged to control the speed and cut into lengths the slower speed web, the cutting means of said couple being adapted to perforate the web and leave the forward sheet connected with the web until separated thereafter, said lower web being fed forward in contact with the higher speed web or webs, means for nipping the webs while in contact with each other and advancing them all at the higher speed, and means for cutting the spaces between the slits to practically sever the half speed web.

3. In a web feeding device for a printing press, the combination with means for feeding a plurality of webs in contact with each other at two different speeds, means for perforating the slower web to form a row of slits across and divide it into sheets before it is brought into contact with the other web or webs, a drag roll for receiving the webs, and a secondary perforating couple for maintaining the sheets at their rear end in registration and perforating the webs in transverse alignment with said slits.

4. In a web feeding device for a printing press, the combination with means for feeding a plurality of webs in contact with each other at different speeds, means for perforating the slower web to form a row of slits across and divide it into sheets, a drag roll for receiving the webs, and a secondary per-

forating couple for maintaining the sheets at their rear end in registration and perforating the webs in transverse alignment, and means for punching through the several layers of paper to maintain side and end register.

5. In a web feeding device for a printing machine, the combination with means for feeding a pair of webs in side registration, of means for feeding a web between them 10 at half speed, means for separating the half speed web into sheets, the means for feeding the slow speed web comprising a pair of cutting cylinders and the means for feeding the high speed web comprising a pair of 15 rolls, one having blunt pins for penetrating through several layers of paper at the margins and drawing the frayed edges through to maintain register.

6. In a web feeding device for a printing 20 press, the combination with means for forwarding a plurality of webs at different speeds, of a cutting couple having means for perforating the slower speed web and leaving the forward sheet connected with the web 25 until separated thereafter, means for nipping the webs in contact with each other at the rear end of each half speed sheet and advancing them all at the higher speed, and means for nipping the webs at the forward 30 end of the sheets for the purpose of maintaining registration of the rear edges and the forward edges of the slower sheet.

7. In a web feeding device for a printing press, the combination of means for introducing a half speed web between a pair of 35 webs running at full speed, means for separating the half speed web into sheets, and means for maintaining the half speed sheets in registration at their rear ends with the 40 pages of the full speed webs.

In testimony whereof I have hereunto affixed my signature.

HENRY A. WISE WOOD.
